UNITED STATES PATENT OFFICE.

JAMES POLK WILLIAMS, OF LATONIA, KENTUCKY.

ELECTRICAL SIGNALING DEVICE.

No. 874,372.

Specification of Letters Patent.

Patented Dec. 17, 1907.

Application filed June 6, 1907. Serial No. 377,576.

To all whom it may concern:

Be it known that I, JAMES POLK WILLIAMS, a citizen of the United States, residing at Latonia, in the county of Kenton and State of Kentucky, have invented certain new and useful Improvements in Electrical Signaling Devices; and I do declare the following to be a full, clear, and exact description of the invention, such as will enable others skilled in the art to which it appertains to make and use the same.

This invention relates to certain new and useful improvements in electrical signaling devices, and especially to a signal for giving notice to two trains approaching each other from the same or opposite directions upon the same track, as, for instance, by arc lights which are displayed in view of the engineer, as in the cab, and if desired, means may be provided to be automatically operated by said signaling mechanism for shutting off the steam and applying the emergency brake.

More specifically used the system of signaling consists in the arrangement of successively arranged sections of insulated electrical conductors, as wires or hollow tubing, on opposite sides of a railway track, each conductor having at a location, preferably in its middle, a bend or elbow whereby one portion of the conducting wire may be laid parallel with and outside of the track. There is a series of sections arranged as above described for each rail, the bending of the section of one rail being located intermediate the bend of the other section, preferably substantially midway.

In utilizing the above described system of conductors, each engine or train is provided with an electrical generator and contact brushes, whereby as two trains approach each other in the same or from opposite directions upon the corresponding sections or portions of the conductors, said conductors will be energized by the generators on the train and lights will be caused to appear in each engine, and thereby give notice of the approach of another engine from the front or rear as the case may be.

Another object of the invention is to provide means for giving a warning if the track should be damaged in any manner, as by a landslide, or the washing out of a bridge, or an obstruction being placed upon the track, as a fallen tree.

Another and important part of the invention resides in the provision of a storage battery carried by or connected with the engine tender which is kept constantly charged by the electrical connections with a generator and so constructed that when the generator is not running, as when the engine is standing still, a current from the battery will be connected to the conductor wires for energizing them and thereby giving a signal in the same manner as though said generator was in operation. Means are provided for automatically connecting the battery with the generator when the train is in motion, but disconnecting it when the train stops. Means are also provided for reversing the brushes when the engine runs backward.

The invention is illustrated in the accompanying drawings, in which;—Figure 1 is a side elevation of an engine equipped with the invention; Fig. 2 is a plan view of a portion of a track provided with my system of conductors and showing three engines thereon; Fig. 3 is a similar view showing one of the engines standing still and the connection between the generator and the storage battery broken; Fig. 4 is a top plan view of a truck provided with my improved connecting mechanism; Fig. 5 is an end view of the truck; Fig. 6 is a cross section of a portion of the track; Fig. 7 is a vertical sectional view of one of the brushes; Fig. 8 is a diagrammatic plan view of a construction adapted for use to indicate damage to the track; Fig. 9 is a broken side elevation of the same; Fig. 10 is a broken side elevation of one means for supporting the conductors; Fig. 11 is a view of part of an engine cab provided with means for setting the air brake.

Referring more particularly to the drawings, A indicates the rails of a track upon opposite sides of each of which is arranged insulated sections B & B' of conductors, which may be formed as rods, wires or hollow tubing. These sections may be of any desired length, preferably about six miles and the intermediate portion of each section is provided with a bend or elbow b which is adapted to be passed under the rail, whereby one end of the section is upon the inside of the rail and the other end of the section is on the outside. The adjacent ends of two sections of conductors are adapted to overlap each other, as it were, with the end of one

section lying upon one side of the rail and the adjacent end of the other section lying upon the other side of the rail, the free ends of each section terminating at a point adjacent to the bent ends or portions of the other sections whereby the conductors are divided into blocks or portions with continuous or unbroken sections of conductors upon each side of both rails, each terminating in a break 10 across which it will be impossible for signals to be transmitted.

Mounted upon or connected with the tender of a locomotive or engine, as by means of a truck C, is a generator D, which 15 is adapted to be actuated in any desired manner, as by means of gearing C² and C³, mounted respectively upon the shaft C' of the truck wheels C and the generator shaft C⁴.

20 The generator can be suspended from the truck in any desired manner, as by means of arms C⁵, and it may be actuated by any other means than the truck wheels, as for instance, steam from the engine, or by a 25 gasoline engine mounted upon the tender but preferably upon a truck C⁷ connected with the engine tender. A brush C⁸ is connected with the generator by means of a wire H and is adapted to engage with the 30 shaft C', whereby electrical communication is established between the generator and the ground through said rail and truck wheels.

Mounted upon the generator truck are the contact brushes D, which may be of any 35 desired construction, but preferably formed as a bar D¹⁰, provided with wires or suitable means for engaging with the conducting wires and preferably supported at its ends by rollers D⁶, which are adapted to roll along 40 the conductors. The bar D¹⁰ is preferably provided with a hollow upright tubular section D⁵ which is adapted to be held telescopically within a section D³ from the truck frame by means of pivoted links or arms D². 45 Coiled springs D⁸ are connected with the tube D⁵ and with the pivotal points of the links D² for holding the bar D¹⁰ against the conductor at all times, thereby insuring a perfect contact irrespective of the movements of 50 the engine. A shield D⁷ is preferably arranged to inclose each brush and a conducting wire D' is arranged to pass up through the tubes D⁵ and E³ and communicate with the signaling apparatus upon the engine, as 55 lights 1 and 2. Two of the brushes D¹⁰ and L for each engine are arranged to engage with the conductors between the rails, and another one K is adapted to engage with the conductors outside of the rail. Said brushes 60 are electrically connected with lights No. 1 and No. 2, and the lights communicate with the ground wire H through the wires N and O, respectively.

In addition to the foregoing means for 65 charging the conductors between two en-

gines by means of the generators D, a storage battery G is provided for each engine, preferably at one end of the motor truck or on the side of the tender, which is adapted to be electrically connected with the generator and the conducting wires of the lighting system, as by means of wires G' and G''. The wire G' leads from one of the brushes D¹⁰ to the battery and the other wire G'' leads from the battery to the wire N between light No. 1 and the conducting wire H. If desired, the wire H may be magnetized after it has flashed a light.

Separable means are provided for breaking the electrical connection between the generator D and the brush D¹⁰ to which the battery G is connected, which preferably consists of a lever E which is pivotally connected with said brush at one end and adapted to have its free end moved into and out of engagement with a contact D⁹ from the generator D. The lever E can be moved in any desired manner, preferably by means of a lever F⁴, which is pivotally connected with the truck at f and connected with the lever at one end by a link F⁵ and has its opposite end in engagement with a collar F² slidably mounted on the shaft of one of the supporting wheels of the tender, or the motor truck, where the latter is used. The collar F² is adapted to be moved back and forth upon said shaft by means of governor arms F³, which are united by means of balls F⁶, in the ordinary manner. When the truck is standing still, the balls F⁶ will be in their retracted 100 position and the end of the lever will be out of contact with the contact D⁹ and the current from the storage battery will be able to pass over the circuits through which the current from the generator passes when the 105 train is in motion.

As above described, it is evident that as soon as two engines approach each other from opposite directions upon the same block or unbroken sections of the conductors, as shown at 100 and 200 in Fig. 2, the current will pass from the generator on each engine to the other engine and cause a light to be flashed from lamp 1 in front of the engineer, thereby notifying each engineer of 110 the approach of another engine. This current will pass from the generator of one engine, as 100, to the brush D¹⁰, which is connected therewith by the lever E, through 115 the conductor B to the brush L of engine 120 200, thence through wire M to lamp I on engines 200, thence through wire N to wire H, where it can pass to the ground through the truck wheel, or be continued through the generator upon engine 200, through its lever E, to brush D¹⁰, thence back through the conductor B', to brush L on engine 100, thence through wire M to the light I on said 125 engine 100, and thence through wire N to the wire H, where it may be grounded 130

through the truck wheels, or it may continue through the generator of engine 100 and continue the course as above described.

By connecting the storage battery G with the generator through the brush D¹⁰ and with the wire N between light 1 and the ground-wire H, the battery is constantly kept charged while the engine is running; but as soon as the engine stops, the connection between the brush D¹⁰ and the generator is broken, as shown on engine 400 in Fig. 2, and the current will then pass from the moving engine over the same circuit, as above described, until it reaches the point beyond lamp 1 where the wire G'' branches off from the wire N, from whence it will pass to the battery G and from there it will pass over the wire G' to brush D¹⁰ of the stationary engine, and thence from the brush D¹⁰ over the section B' of the conductor to the brush L of the moving engine, and then through lamp 2 on said engine, and then back to the generator on said engine, as above described.

When one engine, as 300, is approaching another, as 200, from the rear with a break or bend of one of the conductors between them, and both engines are moving, then the bent section of the conductor between them will be charged or energized by the current passing from the generator of engine 200 through the bent section to the brush K of engine 300, through the lamp 2 over the wires K', O, and H to the ground, as heretofore described, thereby indicating to the engineer of 300 that he is nearing another engine. But if the forward engine is standing still, as indicated at 400 in Fig. 3, then the battery G on 400 will be thrown into action and the current therefrom will pass over the circuit, including the lamps 2 and 1 of 300 and the brushes L of the two engines to and through lamp 1 of 400, and thence to the battery over wire G.

In the drawings, the primary circuits, or those which are generated by the engines as they are moving are indicated by arrows 1', while the circuit from the battery is marked with arrows 2'.

If desired, electro-magnets may be used in connection with the lamps in the cabs for actuating a suitable mechanism for shutting off the steam and applying the emergency brake, as shown in Fig. 11, where 1 and 2 indicate two of the lamps in the cab 12 of the engine; 13 indicates an electric motor in circuit with the lamps, and 14 the brake setting mechanism, which is connected with the motor by a pitman 15. In this manner, whenever a current causes the lamps to glow it will also apply the brakes and thereby stop the train.

Where it is desired to indicate damage to the track, as from a landslide, a missing bridge or an obstruction of any kind, an ad-

ditional wire or conductor B'' is connected with the inner end of each of the conductors and arranged parallel therewith in position to be engaged by an additional brush P on the engine, as shown in full lines in Figs. 8 and 9, and in dotted lines in Fig. 5. In this construction the brushes are shown as pivotally connected with the free ends of arms Q so as to permit of their engaging with the track when the engine is running either forward or backward without danger of breakage. The arms Q are connected with rock shafts R, which are located at opposite ends of a frame or support S and each shaft is provided with an arm T for actuating it. The arms T are connected by a rod U which will cause them to be actuated in unison so as to raise one set of brushes out of contact with the conductors when the other set is lowered. One of the arms T is preferably extended to form a handle by means of which it can be moved, as by means of a cord V, which is connected with the reverse lever of the engine. In this manner when the lever is thrown forward to cause the engine to move forward, one set of brushes will be lowered into contact with the conductors, and when the lever is thrown backward to reverse the engine, the first set of brushes will be raised and the second set will be lowered into contact with the conductors. Where the extra wire or conductor B'' is used, a circuit will be established at all times through the inner or charging conductor, and the extra conductor which will form a return wire of a circuit including the brush D¹⁰ and the brush P. The brush P is connected with the wire H by a wire W, whereby the circuit is completed through the generator D, as heretofore described. The wire W is provided with a lamp 3, which glows at all times when the circuit is complete, thereby indicating to the engineer that the track is all right, up to a predetermined point ahead of him, but if any portion of the track between him and said point should be damaged or obstructed, the circuit will be broken and the lamp 3 will not glow, thereby notifying him of the danger and warning him to proceed with caution. In this construction, the extra conductors are provided with separable joints or contact points, as indicated at X, preferably arranged at about 200 yards apart. The adjacent ends of the conductors P at the breaks X are preferably supported in a forked standard Y and are provided with copper disks or buttons Z, held in yielding contact by coiled springs Z' on the conductors between the buttons and hollow insulators Y' upon the upper ends of the arms of the standard. The conductors pass freely through the insulators so that if any unusual pressure is exerted upon the conductor between two standards, as from a fallen tree or other obstruction, the buttons will be separated, or if any portion

of the conductor be gone, the circuit will be thereby broken and lamp 3 will not glow. The standards Y can be secured in position in any desired manner, as by being bolted to the ties X' of the track.

If it is desired to cause a broken succession of flashes from the lamps in the cab, vertical points or rods may be placed at various intervals by which arrangement when the train is in motion, the current may be carried in broken succession to the lamps in the cab, which lamps may be provided with suitable reflectors. Or the axle may be provided with gearing which, when the engine is moving, will actuate suitable mechanism to make and break the circuit so as to indicate to the engineer on another engine whether the engine which is nearing him from either direction is moving or standing still. By this arrangement, a more noticeable signal will be given to the person in the cab having charge of the engine.

Having thus described my invention, what I claim as new and desire to secure by Letters-Patent is:—

1. In an electric signaling apparatus, a series of independent, alternately arranged conductor sections on opposite sides of a railway track, each conductor section having a bend, whereby portions of each section extend on opposite sides of each line of rails of the track, and signaling apparatus carried by engines, whereby signals may be given in each cab, as circuits are formed, by the approach of engines from opposite directions, on independent conductor wires.

2. In an electric signaling apparatus for locomotives, series of independent, alternately arranged conductor sections on opposite sides of a railway track, each conductor section having an elbow, whereby portions of each section extend on opposite sides of each line of rails of the track, and signaling apparatus carried by a locomotive, whereby signals may be given by the approach of engines in opposite directions, or in the same direction and on the same track, on independent conductor wires.

3. In combination with series of independent and alternately arranged conductor wires, an engine and tender, an electrical generator, a brush contacting with said conductor wires, and having electrical connection with said generator only when the latter is in operation.

4. In an electric signaling apparatus, a generator mounted on a suitable truck and adapted to be operated from the shafts of wheels running on the railway rails, a contact brush, and a governor mechanism designed to establish an electrical connection between said brush and generator, when said truck is moving.

5. In an electric signaling apparatus, a

motor, a contact brush, a pivoted lever having electrical connection with said brush, a governor and connection between the same and said lever, whereby as the truck carrying the motor is moving, the latter is in operation, and electrical connection is established between the brush and motor.

6. In an electric signaling apparatus, a motor provided with a contact point, a contact brush, a tender truck shaft, a sliding collar thereon, governor arms connected to said collar, a pivoted lever having electrical connection with said brush and adapted to be moved into and out of engagement with said contact point, and a lever between said collar and lever, whereby, as the governor is in operation, an electric connection is formed between the motor and brush.

7. In combination with an engine, an electric motor thereon and adapted to be operated thereby, a storage battery, a brush connected thereto, means for charging said battery, arc lights mounted in the cab of the locomotive, and a contact brush on the opposite side of the motor, having electrical connection with the arc light.

8. An electric signaling device for engine cabs, having in combination with conductor wires, arc lights in each cab, a truck carrying a generator, brushes adapted to contact with the inside sections of the conductor wires, an outside brush adapted to contact with an outside section of the conductor wires, means for establishing electrical connections between the brushes and the arc lights in said cabs, and magnetized grounding wires forming part of the circuit of the arc light current.

9. In an electrical signaling apparatus for rail roads, insulated conductors arranged in sections upon both sides of the rails of the track, the adjacent ends of successive conductors overlapping each other, extra conductors connected with the inner ends of said conductors, means for completing electrical circuits through said conductors, and means, for completing electrical circuits through a portion of each of said first-mentioned conductors and the extra conductor connected therewith.

10. In an electrical signaling apparatus, a forked standard, each fork of which is provided with a hollow insulator, conductors having their ends in said conductors, the adjacent ends of said conductors being provided with buttons, and springs on said ends for normally holding said buttons in contact.

In testimony whereof I have hereunto set my hand in presence of two subscribing witnesses.

JAMES POLK WILLIAMS.
